(57) CLAIM

The ornamental design for a bottle, as shown and described.

DESCRIPTION

FIG. 1 is a front elevation of a bottle showing our new design, the opposite side being identical except for the unclaimed showing of the screw threads;

FIG. 2 is a side elevation thereof, the opposite side being identical except for the unclaimed showing of the screw threads; and,

FIG. 3 is a top plan view thereof.

The broken lines in the drawings are for illustrative purposes only and do not form part of the claimed design.
